UNITED STATES PATENT OFFICE.

ERNST BERNHARDT, OF NEWPORT, KENTUCKY.

CIGAR-PERFORATING MACHINE.

SPECIFICATION forming part of Letters Patent No. 396,801, dated January 29, 1889.

Application filed March 12, 1888. Serial No. 266,996. (No model.)

To all whom it may concern:

Be it known that I, ERNST BERNHARDT, a citizen of the United States, and a resident of Newport, in the county of Campbell and State of Kentucky, have invented certain new and useful Improvements in Cigar-Perforating Machines, of which the following is a specification.

My invention relates to that class of perforators in which a frame carrying a number of needles or perforating-points is reciprocated to force the points into and withdraw them from the ends of cigars while they are in the mold.

The invention will be first fully described in connection with the accompanying drawings, and then particularly referred to and pointed out in the claims.

Referring to the drawings, in which each part is indicated by the same reference-letter throughout the different views, Figure 1 is a plan view of my improved machine, having upon it part of a cigar-mold, part of the upper half of which is removed and the cigars shown in central longitudinal section. As shown in this view, the sliding frame has nearly completed its forward stroke. Fig. 2 is an end elevation of the same, having part of the bed broken away to expose the head of one of the bolts by which the frame-guide is secured in place. In this view the frame is represented in its rear position. Fig. 3 is a perspective view of one of the puncturing-points.

The bed-plate A and sliding plate B are preferably made of cast-iron. The bar C, which carries the puncturing-points D, is preferably made of wood.

Upon the bed-plate A, near each end, are cast bars a, which are the lower guide-rests for the sliding plate B. Upon the front is a bar or projection, which is the stop or back rest against which the molds rest. Near the rear edge are two lugs, a', which, when perforated, furnish bearings for the rock-shaft E. Upon the guides a are secured the angle-pieces F by means of bolts f. These pieces F, in connection with the bars a, furnish the guides for the sliding plate B, the ends of which enter the space between the parts a and F and project to the outside to receive the pins which connect the plate B to the crank-arms

E' of the rock-shaft E by means of the links G. Centrally upon the shaft E is secured a lever, H, by which the shaft is rocked and the plate B reciprocated back and forth.

The plate B has an upwardly - projecting flange or face-plate, b, against which the needle-bar C is held by the clamping-buttons b'. Some space is left between the ends of the bar C and the buttons, so that the bar may be adjusted to bring the puncturing-points in the proper position to enter the cigar ends.

The piercers D, Fig. 3, are made of steel and are ground to spear-points, forming cutting-edges d. There are preferably four of these cutting-edges. It has been found that plain cone-pointed needles simply press the tobacco outward as they enter the cigars, and when withdrawn the tobacco again assumes its normal position, thus destroying in a great degree the effect of puncturing. I find that by making the needles spear-pointed or furnishing them with cutting-edges, so as to sever the fibers of the leaf, the tobacco will not again compact together, and cigars so treated will always "draw." Thus the object of perforating cigar ends is perfectly accomplished.

In making my needle-bar the holes are bored the proper distance apart and of slightly less diameter than the piercers D, so that the piercers, when driven in from the back, will be firmly held in the bar. They are driven in until their rear ends are flush with the back of the bar C, so that when the bar is held in the position shown the ends of the piercers will rest against the flange or face-plate b. The piercers D may have a small head, d', formed upon them to prevent possibility of their being drawn forward in their bar; but if properly fitted the head is not essential.

I prefer to construct the device, as shown, with two crank-arms, one upon each end of the rock-shaft, and link these crank-arms to the ends of the sliding needle-bar carrier, because it is cheaper and less liable to get out of order.

Near one end of the bed-plate is a bolt, a³, which stops the mold I in the proper position. Instead of the bar a², which acts as a back-stop, round stud-pins a⁴, as shown in dotted line, may be employed, and I prefer them for the reason that cuttings or scraps of tobacco are not liable to collect back of them and get

between the mold and back-stop. The same result would of course be accomplished by perforating the bed-plate in front of the back-stop.

5 What I claim, and desire to secure by Letters Patent, is—

1. In a cigar-perforating machine, the combination, substantially as specified, of the bed-plate having end guides, a F, lug-bearings a' , 10 and a back-stop, the reciprocating plate B b , movable in said guides, the bar C, and points D, secured in said bar, the buttons b' , for securing said bar to the plate B, having a projecting flange, b , the rock-shaft E, crank-arms 15 E', and links G, connecting said crank-arms to the plate B, and the lever H, secured upon said shaft for the purpose of rocking the same, and thereby imparting a reciprocating movement to the plate B and the piercing-points 20 carried by it.

2. The combination, substantially as specified, of the bed-plate A, having upwardly-projecting bars a a^2 , lugs a' , and stop-bolt a^3 , and the angle-pieces F, secured thereon, the reciprocating plate B, having a projecting flange, 25 b , needle-bar C, and needles D, the buttons b' , to secure said needle-bar in place, the rock-shaft E, crank-arms E', and links G, connecting said crank-arms, and the plate carrying the piercing-points D, and the lever H, secured upon said shaft for the purpose of rocking the same, and thereby actuating the piercers, the whole constructed to operate in the manner set forth. 30
